UNITED STATES PATENT OFFICE

1,936,532

BRASSIÈRE

Joseph A. Weil, New Haven, Conn.

Application April 9, 1932. Serial No. 604,221

2 Claims. (Cl. 2—42)

This invention relates to a brassière, and has for its object to provide, in a manner as hereinafter set forth, a woman's undergarment of such type with extended portions to provide 5 breast receiving pockets without the employment of darts arranged in and secured to the body of the brassière.

A further object of the invention is to provide, in a manner as hereinafter set forth, a 10 garment of the type referred to so constructed and arranged to cover the breasts and worn without any discomforting effect upon the wearer.

Further objects of the invention are to provide, in a manner as hereinafter set forth, a 15 brassière which is simple in its construction and arrangement, strong, durable, light in weight, thoroughly efficient for the purpose intended, pleasing in appearance and comparatively inexpensive to manufacture.

20 To the above ends essentially and others which may hereinafter appear, the invention consists of such parts and such combination of parts of the brassière structure falling within the scope of the invention as claimed.

25 In the drawings:—

Figure 1 is an elevation of the body part of the brassière.

Figure 2 is an elevation of the sections of the body part.

30 Figure 3 is a section on line 3—3 Figure 6.

Figure 4 is a section on line 4—4 Figure 6.

Figure 5 is a fragmentary view in elevation of the body part.

Figure 6 is an elevation of the body part prior 35 to the formation of the breast receiving pockets.

Figure 7 is a perspective view of a brassière in accordance with this invention.

Figure 8 is a section on line 8—8 of Figure 7.

The brassière can be set up with or without 40 several of the edges trimmed, and is illustrated by way of example as having several of its edges trimmed with an edging to enhance the appearance thereof.

The brassière includes a body part 1 formed 45 of a pair of oppositely disposed breast pocket forming members or sections 2, of like form and a combined base and coupling element or section 3 which is common to the sections 2, and each of the latter is formed of a flat piece of suitable 50 fabric of angled contour having an upstanding portion 4 and a horizontal portion 5 extending inwardly from the lower part of portion 4.

Each section 2 has an out curved lower edge 6 55 which is common to portions 4, 5. The portion 4 has an inclined outer edge 7, the latter extending

inwardly from its lower to its upper end. The top edge 8 of portion 4 inclines downwardly from its outer to its inner end. The inner edge 9 of portion 4 from the inner end of edge 8 extends upon an inwardly extending curve throughout. 60 The inner edge 10 of portion 5 is straight. The top edge 11 of portion 4 is upon an arcuate curve from its outer end to the point of mergence at its inner end with the lower end of the inner edge 9 of portion 4. The portion 5 increases in height 65 from its outer end to its point of mergence with portion 4.

The section 3 is of belt like form and consists of a length of fabric bent upon itself to provide a 70 pair of folds 11', 12 and between the free longitudinal edges of the latter extends the lower marginal portions of the section 2. The section 3 is secured to the sections 2 by a row of stitching 13, and the former when secured to section 1 have the edges 10 thereof arranged in opposed spaced 75 relation.

The first step of the method is the arranging of the lower marginal portions of a pair of oppositely disposed pocket forming members of 80 angled contour and of like shape, in spaced relation, between the free longitudinal edges of the combined base and coupling section 3. The sections 2 are then secured to section 3 by the row of stitching 13.

After the sections 12 and 13 are secured together by the stitching 13, the section 3 is folded at its transverse center upon itself, as at 14, to provide for the sections 2 to be arranged in a manner whereby the bottom edge of each will extend at an upward inclination from its outer to its inner end, the outer edge of each vertically disposed, the upper edges of portions 4 from the outer to the inner ends thereof at an upward inclination, and the inner edges of portions 5 at 85 opposite inclinations with respect to each other. 90 The folding of section 3 at its transverse center forms it with a pair of curved parts 15, 16 which extend at an up curve from their outer towards their inner ends. The folding of section 3 at its transverse center also provides a triangular shaped portion 17 initially opposing part 16, but such portion 17 is folded back upon part 15. The central portion of section 3 has applied thereto 95 rows of stitching 18, 19 and 20 which not only secure the folds 11, 12 together, but also secure portion 17 to part 16. The sections of the body part 1 will appear as shown in Figure 6, when the section 3 is folded and secured together at its center.

The edges 9 and 11 of each section 2 are then 100

coupled together by any suitable means, and by way of example a narrow oblong strip of lace 21 is employed and which is secured to the section 2 adjacent edges 9 and 11 thereby shaping the 5 section into a breast receiving pocket 22, with the edges 8 and 10 being a substantial continuation of each other, disposed at an inclination and at an opposite inclination with respect to the edge 7, and with the inclination of the latter being 10 greater than that of edges 8 and 10. The edges 7 and 8 extend towards each other from their lower to their upper ends when the edges 9 and 11 are coupled together. When the edges 9 and 11 of each section 2 are secured together the latter and 15 section 3 will appear as shown in Figure 6.

The brassière includes resilient body straps 23 attached to the ends of section 3 and having co-acting means 24 at their free ends for detachably connecting them together. The straps 23 may be 20 connected to sections 3 before or after it is folded at its center.

The brassière includes a pair of shoulder straps 25 attached to the sections 2 and to the straps 23. The shoulder straps 25 may be attached at one 25 end to sections 2 before or after section 3 is folded at its center and at their other ends to straps 23 before or after the latter have been secured to section 3.

When the edges 9 and 11 of each section 2 are 30 coupled together each section 2 is extended outwardly with respect to section 3 and each part 15, 16 of the latter is disposed substantially vertically with respect to the bottom of a section 2.

What I claim is:—

35 1. A brassière comprising a combined base and coupling element of belt-like form folded upon itself at its transverse center, means for fixedly securing the folded portion of said element to the remaining part thereof to provide a pair of oppositely extending curved parts, a pair of oppositely disposed spaced sections of angled-form secured at their lower ends to said curved parts, each of said sections including an upstanding portion and a horizontal portion extending inwardly from the lower part of said upstanding portion, the latter being formed with an outer side edge inclining outwardly from its upper to

its lower end, a top edge inclining downwardly from the upper end of said outer side edge and an inner side edge of less length than said outer side edge and curved inwardly from the inner end of said top edge, said horizontal portion having a straight inner side edge and an arcuate top edge, and means for coupling throughout the inner side edges of the upstanding portions to the top edges of the horizontal portions to position the top edges of the upstanding portions in lengthwise alignment with the inner side edges of the horizontal portions to provide a pair of oppositely disposed spaced breast receiving pockets extending outwardly from the top edge of said curved parts.

2. A brassière comprising a combined base and coupling element of belt-like form folded upon itself at its transverse center, means for fixedly securing the folded portion of said element to the remaining part thereof to provide a pair of oppositely extending curved parts, a pair of oppositely disposed spaced sections of angled-form secured at their lower ends to said curved parts, each of said sections including an upstanding portion and a horizontal portion extending inwardly from the lower part of said upstanding portion, the latter being formed with an outer side edge inclining outwardly from the upper to the lower end, a top edge inclining downwardly from the upper end of said outer side edge and an inner side edge of less length than said outer side edge and curved inwardly from the inner end of said top edge, said horizontal portion having a straight inner side edge and an arcuate top edge, and means for coupling throughout the inner side edges of the upstanding portions to the top edges of the horizontal portions to position the top edges of the upstanding portions in lengthwise alignment with the inner side edges of the horizontal portions to provide a pair of oppositely disposed spaced breast receiving pockets extending outwardly from the top edge of said curved parts, said horizontal portion of each section gradually increasing in height from its inner side edge to its point of mergence with the upstanding portion of the section.

JOSEPH A. WEIL.
